UNITED STATES PATENT OFFICE.

RICHARD DIETSCH, OF EDGERTON, OHIO.

DESIGN FOR A RADIATOR-CAP ORNAMENT.

Application filed November 15, 1928. Serial No. 28,904. Term of patent 7 years.

To all whom it may concern:

Be it known that I, RICHARD DIETSCH, a citizen of the United States of America, residing at Edgerton, in the county of Williams and State of Ohio, have invented a new, original, and ornamental Design for a Radiator-Cap Ornament, of which the following is a specification, reference being had to the accompanying drawing, forming a part hereof.

In the drawing:

Figure 1 is a plan view of a radiator cap ornament showing my design,
Fig. 2 is a front elevation of the same, and
Fig. 3 is an end elevation thereof.

I claim:

The ornamental design for a radiator cap ornament, as shown.

RICHARD DIETSCH.
